UNITED STATES PATENT OFFICE.

CHARLES T. THOMAS, OF STANLEY, NORTH CAROLINA.

OIL SHIELD FOR RING RAILS.

Application filed May 27, 1922. Serial No. 564,108.

To all whom it may concern:

Be it known that I, CHARLES T. THOMAS, a citizen of the United States, residing at Stanley, in the county of Gaston and State 5 of North Carolina, have invented a new and useful Oil Shield for Ring Rails, of which the following is a specification.

This invention relates to an oil shield for ring rails for twisting machines.

10 The object of the invention is to provide a shield to protect the yarn against oil thrown out by the traveler and to prevent a broken yarn from flapping in the oil and thereby soiling not only the yarn on the 15 bobbin carrying it, but that of adjacent bobbins.

With the foregoing and other objects in view which will appear as the description proceeds, the invention resides in the combination and arrangement of parts and in the details of construction hereinafter described and claimed, it being understood that changes in the precise embodiment of the invention herein disclosed may be made 25 within the scope of what is claimed without departing from the spirit of the invention.

In the accompanying drawings:—

Figure 1 represents a bottom plan view 30 of a ring rail equipped with this improved shield.

Fig. 2 is a transverse section thereof, taken on the line 2—2 of Fig. 1, the ring rail and the shield being in inverted position.

35 Fig. 3 is a similar view taken on line 3—3 of Fig. 1.

Fig. 4 is a sectional view.

In the embodiment illustrated, a ring rail 1 is shown such as is usually employed in 40 wet yarn twisting machines, and which is equipped with the usual rings 2. The ring rails are made in sections and each section, one of which only is shown herein, is equipped with two traveler stand rods 3 45 and has twenty-one to twenty-two spindles in each section.

The shield constituting this invention comprises a metal plate or section 5 of a length and width corresponding to the ring 50 rail 1 and has openings 6 therein which register with the rings 2, and have mounted therein tubular sleeves 7 which constitute the shields proper, and which extend into

and through the rings 2 between which and the rings the traveler 4 is mounted. 55

The shields proper or sleeves 7, one of which is carried in each opening 6 is secured to the plate 5 by any suitable means, being here shown bolted to the lower face of the plate 5 by means of laterally extending slot- 60ted lugs 8, which are here shown extending at diametrically opposite points from the sleeves which extend through plate 5 and also span the space between this plate and the ring rail. These sleeves 7 are prefer- 65ably constructed of brass to avoid rusting incident to the contact therewith of the wet yarns, the plate 5 may be of any suitable sheet metal not necessarily of brass, since the yarns do not contact with it. 70

The plate 5 is shown provided along one edge with a right angularly extending flange 9 provided along its free edge with a laterally and outwardly extending lip 10, adapted to fit under a cooperating lip 11 75 carried by the ring rail, the lip on the plate 5 being shown resting on the lip of the ring rail and the unflanged edge of said plate rests on the edge of the flange 12 forming a part of the rail 1. The standard rods 3 are 80 shown provided with blocks 13 arranged between the plate 5 and the ring rail 1 and on which the shield plate 5 rests.

From the above description it will be obvious that the shield plate or section 5 fits 85 directly beneath the ring rail 1 and moves with the travelers, the same as the rail. This shield may be adjusted on the section which carries it to fit each ring so that the traveler may run freely. 90

When the ring rail 1 is removed, the shield section or plate 5 remains, said plate and rail being independent of each other although connected when in use. 95

In the use of this invention, the sleeve- 95 like shields 7 being inserted in the rings shown in the drawings, the bobbins carrying the yarn extend through these sleeves so that any oil thrown out by the traveler will not reach the yarn, and should the yarn 100 break, it cannot get under the ring and become soiled, as is the case when the shield is not used.

It will be seen that this shield may be constructed as articles of manufacture, and 105 applied to the ring rails of twisters already

in use without necessitating any change being made in the ring rail to which it is applied.

I claim:

- 5 1. The combination with a ring rail for twisting machines; of an oil shield comprising a plate to be mounted below said ring rail, and having sleeve-like shields for insertion in the rings of said rail.
- 10 2. The combination with a ring rail for twisting machines; of an oil shield com-

prising a plate to be mounted below said ring rail, and having sleeve-like shields for insertion in the rings of said rail, said sleeves being detachably mounted on said plate. 15

In testimony that I claim the foregoing as my own, I have hereto affixed my signature in the presence of two witnesses.

CHARLES T. THOMAS.
